ATTORNEY

UNITED STATES PATENT OFFICE.

WLADISLAW KWIATKOWSKI AND HIPOLIT WIESCHON, OF ASTORIA, NEW YORK.

CHAIN-GRADE STOKER CLIP.

Application filed March 19, 1924. Serial No. 700,245.

To all whom it may concern:

Be it known that WLADISLAW KWIATKOWSKI and HIPOLIT WIESCHON, citizens of Poland, residing at Astoria, Long Island,

5 in the county of Queens and State of New York, have invented certain new and useful Improvements in Chain-Grate Stoker Clips, of which the following is a specification.

10 This invention has general reference to mechanical stokers for furnaces, of the type known as chain grate stokers, and which comprise an endless grate element mounted on suitable supports and which travels along 15 the fire chamber.

This invention has particular reference to one of the units, or clips, which form the grate, and it has for an object the provision of a novel clip constructed to permit of 20 ready replacement of individual clips when desired, without effecting the grate structure as a whole.

For further comprehension of the invention, and of the object and advantages 25 thereof, reference will be had to the following description and accompanying drawing, and to the appended claims in which the various novel features of the invention are more particularly set forth.

30 Fig. 1 of the drawing is an underside perspective view of one form of our improved clip.

Fig. 2 is a fragmentary underside plan view showing a number of clips in assembled 35 relation.

Fig. 3 is a transverse sectional view taken on the line 3—3 of Fig. 2.

Fig. 4 is a like view to Fig. 2, but showing a modified construction.

40 Fig. 5 is a fragmentary perspective view of the retractile element of the clip shown in Fig. 4.

Fig. 6 is a side view showing another form of clip.

45 As here embodied our improved chain grate clip comprises a bar 10 which is suitably curved or arched longitudinally on its outer side, and is formed with grooves 11 to permit of passage of air. The bar 10 has 50 its ends formed the usual manner complementary to one another. In grate clips as ordinarily constructed the clip or bar is formed with a pair of integral claws on its inner side which grip a transverse supporting member and thereby are held in place, this construction being disadvantageous in

that if one clip is broken, as frequently happens, the whole row of clips may have to be dismounted to permit of replacing the broken 60 clip.

To obviate this difficulty we form the bar 10 with only one integral claw 14 which engages one side of the support, while the other side of the support is engaged by a movable claw 15 which is formed on a slide 65 block 16 mounted on a flat surface 17 on the inner face of the bar and which is guided by means of a pair of rods 18 which extend along the bar and are fixed at their opposite ends to the latter, these rods passing 70 through grooves 19 in the side of the claws, at the base thereof, and thereby holding the block against lateral displacement. The surface 17 is of sufficient length to permit of the block 16 being drawn back sufficiently to 75 free the claw 15 from the supporting element.

To hold the block 16 in position with the claw thereof engaging the supporting element we may provide the tension spring 20 80 shown in Fig. 6 and which is connected at opposite ends respectively to the block and the bar 10 and which is located in a suitable recess in the bar. Instead of this spring we may employ a locking bolt or 85 strap 25 which extends from side to side of the grate, being passed behind the blocks 16 and between the surface 17 and the rods 18 and thereby acts to hold the blocks against movement to release the claws 15. This 90 strap 25 may have one end inturned laterally as at 26 and secured as by the screw 27 to the side clip of the grate or to any other suitable or usual side element on the grate, the end 26 of the strap being here shown as 95 recessed at 28 to receive the head of the screw 27.

In the form of the invention shown in Fig. 4 we substitute for the strap 25 a slightly different one 25' which has a number of notches or recesses 30 formed in the side thereof which engages the blocks 16, while the latter are also formed with recesses 31 on their adjacent ends into which the tongues or projections on the strap 25' 105 between the recesses 30 in the latter may be received when the strap is slightly shifted. The parts are otherwise as above described, except that it will be understood that they are so proportioned that the claws 15 on 110 any block 16 may be freed by moving the end of the block into the recess 30 in the

strap. This construction has the advantage over that shown in Fig. 3 in that the strap need only be moved longitudinally a slight distance to free the claws 15.

Having thus described our invention what we claim as new and desire to protect by Letters Patent of the United States is as follows:

1. A clip for chain grate stokers comprising a bar having an integral claw on its rear face, and presenting a flat surface on its rear face adjacent the said claw, a block mounted slidably on said flat surface and having a claw thereon adapted to co-operate with the said integral claw, guide means for said block comprising a pair of rods mounted on the bar and extending substantially parallel to the said flat surface and passing through grooves in the opposite sides of the block, and means releasably holding the said block in normal position with the claw thereon co-operating with the integral claw on the clip.

2. A clip for chain grate stokers comprising a bar having an integral claw, a slide block on said bar, and a claw on said slide block adapted to cooperate with the first

claw, and a guide element for said block comprising rods mounted on the bar and passing through grooves in the sides of the block, means for locking said slide block comprising a strap inserted behind said block and retained against transverse displacement by said rods.

3. A clip for chain grate stokers comprising a bar having an integral claw, a slide block on said bar, and a claw on said slide block adapted to cooperate with the first claw, and a guide element for said block comprising rods mounted on the bar and passing through grooves in the sides of the block, means for locking said slide block comprising a strap inserted behind said block and retained against transverse displacement by said rods, said strap being formed with a recess in the side thereof adjacent the block, and said block having its adjacent end formed with a recess, for the purpose set forth.

In testimony whereof we have affixed our signatures.

WLADISLAW KWIATKOWSKI.
HIPOLIT WIESCHON.
